UNITED STATES PATENT OFFICE.

FREDERICK W. HALL, OF CAMDEN, NEW JERSEY, ASSIGNOR OF ONE-HALF TO J. W. PAXSON COMPANY, OF PHILADELPHIA, PENNSYLVANIA, A CORPORATION OF PENNSYLVANIA.

MOLDING-MACHINE.

SPECIFICATION forming part of Letters Patent No. 761,224, dated May 31, 1904.

Application filed July 11, 1903. Serial No. 165,045. (No model.)

To all whom it may concern:

- Be it known that I, FREDERICK W. HALL, a citizen of the United States, and a resident of Camden, in the State of New Jersey, have 5 invented certain new and useful Improvements in Molding-Machines, of which the following is a full, clear, and exact description, reference being had to the accompanying drawings, forming a part of this specification.
- 10 The invention to be hereinafter described relates to molding-machines, and more particularly to that type wherein the flask containing the sand, patterns, and connected parts is moved upward under suitably-controlled 15 power-operated devices against a cross-head for properly compressing or ramming the sand in the flask.

The general objects of the invention are to provide such type of machine wherein the 20 parts shall be simple in construction, readily operable for the purpose of ramming the sand about the patterns, and thereafter separating the patterns from the mold-cavities and wherein the different operations shall have such dependent relations to the position of the cross-head that improper manipulation of the machine by careless or inattentive operatives is 25 rendered practically impossible.

With these general objects in view the invention consists of a double telescoping base 30 portion conjointly and independently operable for simultaneously or independently raising and lowering the combined stripping and pattern plate supports and the stool-plate support, a cross-head movable into position above or to one side of said supports, and means for controlling the operation of the combined stripping and pattern plate support and the stool-plate support, so that when the cross-head 35 is in position above these parts all of them may be simultaneously raised to effect the proper ramming of the sand in the flask and about the patterns without possible independent movement of the supports, and when the cross-head is moved to one side of such 40 position then simultaneous movement of the supports is prevented, and only movement of the stool-plate support is possible.

In addition to these separate and combined elements the invention further consists of the 50 parts and combinations, as will be hereinafter more fully described and then definitely pointed out in the claims.

In the drawings, Figure 1 is a side elevation of the machine, the piping being omitted to more clearly present the remaining structure. Fig. 2 is a front elevation looking in the direction of the arrow in Fig. 1. Fig. 3 is a detail view of the cross-head supporting-arms and pivotal connection with the 60 base, showing the manner of operating said arms. Fig. 4 is a detail view, partly in section, of the base, the combined stripping-plate and pattern-plate support, the stool-plate support, showing also the telescoping parts for 65 simultaneous and independent operation of said supports. Fig. 5 is a detached front elevation of one of the cross-head side or supporting arms with some of the details omitted to more clearly show the piping for operating the different parts. Fig. 6 is a side view of the parts shown in Fig. 5 looking in the direction of the arrow, Fig. 5, some of the details being broken away to avoid confusion; and Fig. 7 is a detail sectional view of the auxiliary controlling-valves.

Referring to Figs. 1 and 2, A is the supporting-base of the apparatus, and it may be of any usual or desired form. Rigidly mounted upon said support is the casting A', Figs. 80 2 and 4, preferably cylindrical, which constitutes the interior telescoping guide for the exterior main cylinder A'', having the head A'', from each side of which project the supporting-brackets A''. The upper surface A⁵ A⁵ of 85 the supporting-brackets A'' A'' constitutes the stripping-plate support, and projecting from the inner sides of these brackets are the lugs A⁶ A⁶, constituting the pattern-plate supports, the said stripping-plate supports and pattern-plate 90 supports being thus formed, preferably, in an integral structure, although, as will be obvious, this integral formation is not essential so long as the supports A⁵ and A⁶ are connected to move in unison, and I may designate them 95 for identification as the "combined stripping-

plate and pattern-plate support." Projecting inward of the casting or guide A' is the flange *a*, to which is secured a fixed cylinder B, Fig. 4, by means of a suitable flange *b* and bolts *b'*, 5 although any usual or desired fastening means may be employed to retain the cylinder B fixed within the casting A'. Telescoping within the fixed cylinder B is an interior or stool-plate plunger B', preferably made as a hollow 10 casting for lightness and to fit the cylinder B, its entire length to act as a guide for the plunger in its up and down movements, the lower end of the plunger being closed by the head *b*. Secured to the upper portion of the plunger B' is the stool-plate support C, having the 15 upwardly-extending posts *c c*, the upper surfaces *c' c'* of which are substantially in the plane of the stripping-plate support A⁵, as seen in Fig. 1. Projecting from each of the 20 corners of the stool-plate support C are the perforated lugs *c' c'*, which, passing through suitable vertical slots in the supporting brackets A⁴ A⁴, embrace the guide-rods *c' c'*, which extend between the side lugs *c' c'* at the sides 25 of brackets A⁴ A⁴, whereby when rising or falling movement is given the stool-plate support with relation to the combined stripping-plate and pattern-plate support said rods *c' c'* serve to steady the stool-plate support and 30 arms *c c* and guide the same accurately. By referring to Fig. 4 it will be noted that between the flange *b* of the cylinder B' and the under surface of the head A³ there is a space into which leads a fluid-supply pipe M for 35 raising the main cylinder and its connected stripping and pattern plate supports A⁵ and A⁶, and it will also be noted that as said main cylinder A² is thus raised by air or other fluid it will carry with it the stool-plate support C, 40 since the head A³ of the main cylinder will engage the under surface of the stool-plate support in its upward movement. Likewise connected to the cylinder B below the plunger B' is the pipe N for supplying a suitable 45 liquid, such as compressed air or the like, to the said cylinder B to thereby raise the stool-plate support independent of any movement of the combined stripping-plate and pattern-plate support, as will be readily understood 50 by reference to Fig. 4. The piping connections for the supply of fluid-pressure will be hereinafter more fully described.

It is desirable in this class of devices that the combined stripping-plate support and pattern-plate support shall move vertically, and in order to accomplish this result more efficiently I have provided the exterior main cylinder A² with side lugs A⁷, having suitable vertical perforations which embrace fixed guide- 55 rods A⁸, as shown in Fig. 2, extending upward from the base of the telescoping guide A'. These guide-rods A⁸ extend into suitable recesses in the lower part of the combined stripping-plate and pattern-plate support, whereby 60 said support is guided in its up-and-down

movement, and in order that the downward movement of the main exterior cylinder A² shall not transmit shocks and other undesirable vibrations and jars I have provided in the lower part of the lugs A⁷ recesses A⁹, and 70 seated in these recesses springs A¹⁰ have been provided, which serve to check in a gradual manner the downward movement of the main exterior cylinder A² and consequently give a yielding check to the downward movement 75 of the combined stripping plate and pattern-plate support, as will be obvious.

From the construction thus far described it will be seen that upon the admission of air or other motive fluid through the supply-pipe M from the main cylinder both the combined stripping-plate and pattern-plate support and the stool-plate support will be moved in a vertical direction simultaneously to thereby carry toward the cross-head, which is at this 85 time disposed above said parts, the flask with the contained patterns, as will be understood, and that by such vertical movement of these parts simultaneously the necessary ramming or compression of the sand in the flask and 90 about the pattern will be secured. Upon the exhaust of the fluid through the pipe M these parts will conversely simultaneously move to the lowered position, as shown in Figs. 1 and 4, the stool-plate support at such times resting by its weight upon the head A³ of the exterior main cylinder A², as will be understood, and thereby partaking of its movement. The action thus described having rammed the sand in the flask, it becomes necessary to withdraw 95 the patterns from the sand, and this is secured by the admission of the motive fluid through the pipe N beneath the interior cylinder or plunger B', whereupon the stool-plate support C, with its upward-extending arms *c*, will be 100 moved upward, during which time the combined stripping-plate support and pattern-plate support will remain stationary. This movement of the stool-plate support C will engage by the upper surfaces of the arms *c* 105 the stripping-plate and raise it, together with the flask, away from the patterns, as will be obvious.

Pivoted to the upward-extending brackets D', secured to the supporting-base A, are the side arms D D of the cross-head D², the pivotal connection of said arms to the portions D' being shown in Figs. 1, 2, and 3 as formed by suitable bolts D³ D³, suitable stops D⁴ D⁴ being provided to limit the swinging movement of the side arms of the cross-head upon their pivots D³. The cross-head D² may have secured thereto at its under surface a suitable block, as D⁵, of a size to effect the proper ramming of sand in the flask, the said cross-head being carried by an adjusting-screw D⁶, projecting upward from the side arms D and held in adjusted position by suitable clamping-nuts D⁷. In order to effect the movement of the cross-head, a simple cylinder d is 110

provided, the same being pivoted at d' to a bracket d^2 , said cylinder having connected thereto a suitable pipe, as O, for the supply of motor fluid thereto in any suitable manner, 5 so as to effect the desired reciprocation of the piston in said cylinder. The details of this connection of the fluid-supply pipe O to the cylinder d form no part of my present invention, and as they are well within the scope of 10 the ordinary mechanic further detailed description thereof will be unnecessary. The piston d^3 of said cylinder (shown by dotted lines in Fig. 3) is connected by a rod d^4 to a link d^5 , which is itself pivoted at d^6 to the side 15 arms of the cross-head, as shown in Figs. 1 and 3. The pivotal connection of the cylinder d to the bracket d^2 serves to turn said cylinder slightly, due to the rising-and-falling movement of its pivotal connection d^6 with 20 the side arms of the cross-head, as will be understood. Referring to Fig. 3 more particularly, it will be noted that the side arms of the cross-head project some distance below the pivots D^3 , and said lower projecting portion 25 of the side arms is provided with a slot, as d^7 , in which fits a pin d^8 of a link d^9 , said link having connected thereto the rods d^{10} , preferably formed as shown in Fig. 3. Suitably secured to the base of the device is a bracket d^{11} , 30 having pivoted at d^{12} a cylinder d^{13} , carrying a spring d^{14} , disposed between the cross-head d^{15} , connected to the rods d^{10} and the head d^{16} of the cylinder, whereby as the side arms of the cross-head swing upon their pivots d^3 said 35 spring is compressed within the cylinder, as shown in Fig. 3, and serves to cushion the downward swinging movement of the cross-head as the side arms thereof approach the stops D^4 , said spring also serving to return 40 the cross-head to its upright position when the motor fluid from the cylinder d exhausts.

As thus far described it will be noted that the entire operation of the moving parts of the device is effected by fluid action, such as compressed air or the like, and in order that the operative may at all times have the controlling instrumentalities in convenient position for his ready manipulation I have disposed the piping and valves leading to the various 45 cylinders as shown in Figs. 5, 6, and 7.

Connected to one of the side arms D of the cross-head is a hood or cover E, extending upward and terminating in a supporting-bracket E' in position to be within the reach of the operative. Communicating with a suitable source of compressed air or other fluid-supply 55 is a pipe G, Figs. 5 and 7, connecting, by means of suitable valves H and I, Figs. 5, 6, and 7, to be described, with the pipes M and N, said 60 pipes being carried, as shown in Figs. 5 and 6, upward within the hood or cover E to the bracket E', where each is provided with a suitable two-way cock M' and N', respectively. The detail construction of these two-way cocks 65 M' and N' forms no part of my present invention, and as they are well understood by those skilled in the art it is unnecessary to elucidate the matter in this connection, such cocks being simply for the admission and exhaust of the air or other fluid to and from the main 70 cylinder A² and the interior cylinder B for raising and lowering the stripping and pattern plate supports and the stool-plate support, respectively. From the valves M' and N', respectively, the pipes M and N return 75 downward within the hood or cover E and connect with the inlets to the main and interior cylinders, as shown in Fig. 4. Also carried upward and returned within the hood or cover E is the pipe O, which is in constant communication with a source of compressed air or other fluid-supply, as at O², Fig. 5, said pipe O being provided with a suitable two-way cock O' of any usual or desired construction, 80 whereby at all times the supply of air or other fluid to or from the cylinder d for swinging the cross-head D² from above the stripping-plate and pattern-plate supports may be controlled. By this disposition of the piping connection and the valves for controlling the 85 fluid-supply the operative has at all times in convenient position the means for controlling all the operating parts.

It is desirable that the exterior main cylinder shall be capable of being raised only when 90 a flask is to be rammed—that is, when the cross-head D² is in position above the combined stripping-plate and pattern-plate support—and that the interior cylinder or plunger connected to the stool-plate support shall be 95 capable of being independently raised for stripping the flask and mold from the patterns only when the cross-head is moved from its position above the combined stripping-plate and pattern-plate support, and to this end I 100 have provided the valves H and I, hereinbefore referred to.

The pipe G', which connects directly with the supply-pipe G, extends parallel to the plane of movement of the side arms D of the 105 cross-head and separated a short distance therefrom, as shown in Figs. 5, 6, and 7. Disposed crosswise of the pipe G' at each side of the main supply-pipe G are the valves H and I, which for identification may be designated 110 the "auxiliary" valves. These valves each comprise a plug t, having a perforation t' and an extended stem t², provided with a beveled head t³, said plug t being normally pressed in the direction of its head by means of a spring 115 t⁴, disposed between the closed end t⁵ of the tube t⁶, in which the plug t slides, and the plug t. The tube t⁶ is also provided with a perforation t⁷, which when the plug t is pressed inward by the stress of its spring will register 120 with the perforation t' in the plug and allow the compressed air or other fluid to pass into the pipes M and N, according to which of the valves is so acted upon, so that thereafter by manipulation of the cocks M' or N' 125 130

the outer or inner cylinder A² B, respectively, may be raised and lowered. The heads of the valves H and I extend into the path of movement of one of the side arms D of the 5 cross-head, so that when the guide-arm moves into engagement with either head it will move the valve back against the stress of its spring and close communication between the main supply-pipe G and the pipe controlled 10 by the valve so acted upon. The valve I controls communication between the supply-pipe G and the pipe M for operating the exterior main cylinder A², and it is so disposed in pipe G' that when the cross-head is in its raised 15 position and directly above the stripping-plate and pattern-plate support the side arm of the cross-head is not in contact with the head of the valve, as shown in Figs. 6 and 7, so that communication is established between 20 the supply-pipe G and pipe M, operating the exterior main cylinder. When, however, the cross-head is swung to one side, the side arm D contacts with the head of valve I and pressing back that valve shuts off communication 25 between the supply and pipe M, so that the exterior main cylinder carrying the stripping-plate and pattern-plate supports cannot be raised. So, also, with respect to valve H. It is disposed with relation to the side arm D of the 30 cross-head so that when the cross-head is in position over the stripping-plate and pattern-plate supports the side arm D is in contact with the head of valve H and pressing back that valve against its spring shuts off communication 35 between the main supply G and pipe N for operating the interior cylinder or plunger carrying the stool-plate support, so that the stool-plate support cannot be raised, except as it is raised by the exterior main 40 cylinder, and when the cross-head swings to one side the side arm D releases the valve H to the action of its spring, which opens communication with pipe N, so that at such time the interior cylinder or plunger may be raised 45 independently of the exterior main cylinder, which latter at such time is rendered inoperative by its valve I.

From the construction described it will be seen I have provided a main exterior cylinder 50 for carrying the stripping-plate support and the pattern-plate support, and within this main cylinder I have compactly arranged the interior or secondary cylinder for raising and lowering the stool-plate support, 55 said cylinders, as well as the cylinder for swinging the cross-head, being operated by means of compressed air or other fluid. By the arrangement also of the auxiliary valves H and I in the fluid-supply conduits I have 60 provided means to render the raising of the main cylinder impossible when the cross-head is swung to one side or from over the stripping and pattern plate supports and to also render it impossible to raise the stool-plate support when the cross-head is in position 65

above the stripping-plate and pattern-plate supports, thus providing an automatic means for preventing improper manipulation of the device. The upwardly-projecting arms carried by the stool-plate support having their 70 upper surfaces substantially in the plane of the stripping-plate supports enables the said arms to raise the stripping-plate and the parts resting thereon upward and away from the patterns when the latter are to be drawn from 75 the flask.

Having thus described my invention, what I claim, and desire to secure by Letters Patent, is—

1. In a molding-machine, the combination 80 of a main exterior cylinder carrying the stripping-plate support and the pattern-plate support, a secondary cylinder or plunger disposed within the main exterior cylinder and carrying the stool-plate support, means for supplying fluid-pressure to the main exterior cylinder to thereby simultaneously raise the stripping-plate support, the pattern-plate support, and the stool-plate support, and means for supplying fluid-pressure to the secondary cylinder 85 90 to operate the stool-plate support independent of the stripping-plate and pattern-plate supports.

2. In a molding-machine, the combination 95 of a main exterior cylinder carrying the stripping-plate support and pattern-plate support, a secondary cylinder or plunger disposed within the main exterior cylinder and carrying the stool-plate support independent of the main exterior cylinder, said stool-plate support having upwardly-projecting portions the upper surfaces of which are in the plane of the stripping-plate support, means for supplying fluid-pressure to the main exterior cylinder to thereby simultaneously raise the stripping-plate support, the pattern-plate support, and the stool-plate support, and means for supplying fluid-pressure to the secondary cylinder 100 105 to operate the stool-plate support independent of the stripping-plate and pattern-plate supports.

3. In a molding-machine, the combination 110 of a main exterior cylinder carrying the stripping-plate support and the pattern-plate support, a secondary cylinder or plunger disposed within the main exterior cylinder and carrying the stool-plate support, the exterior cylinder having guide-rods, said stripping-plate support having lugs or projections for engaging 115 said guide-rods, means for supplying fluid-pressure to the main exterior cylinder to thereby simultaneously raise the stripping-plate support, the pattern-plate support, and the stool-plate support, and means for supplying fluid-pressure to the secondary cylinder to 120 125 operate the stool-plate support independent of the stripping-plate supports.

4. In a molding-machine, the combination 130 of a main exterior cylinder having side projections, and carrying the stripping-plate sup-

- port and pattern-plate support, a secondary cylinder or plunger disposed within the said main cylinder and carrying the stool-plate support, guide-rods engaging the side projections of the main exterior cylinder, cushioning devices to check the downward movement of the exterior cylinder and means for supplying fluid-pressure to the main exterior cylinder to thereby simultaneously raise the stripping-plate support, the pattern-plate support, and the stool-plate support, and means for supplying fluid-pressure to the secondary cylinder to operate the stool-plate support independent of the stripping-plate and pattern-plate supports. 5
5. In a molding-machine, the combination of a supporting-frame or base, guide-rods extending upward therefrom, a main exterior cylinder having side projections for engagement with said guide-rods and carrying the stripping-plate and pattern-plate supports, a secondary cylinder or plunger arranged within the main exterior cylinder and carrying the stool-plate support and provided with side projecting portions, guide-rods carried by the main exterior cylinder and engaged by the said projecting portions of the stool-plate support, and means for supplying fluid-pressure to the main exterior cylinder to thereby simultaneously raise the stripping-plate support, the pattern-plate support, and the stool-plate support, and means for supplying fluid-pressure to the secondary cylinder to operate the stool-plate support independent of the stripping-plate and pattern-plate supports. 25
6. In a molding-machine, the combination of a main exterior cylinder having upwardly-projecting arms, stripping-plate supports and pattern-plate supports carried by said arms, a secondary cylinder disposed within the main exterior cylinder and carrying the stool-plate support, arms projecting upward therefrom and having their upper surfaces in the plane of the stripping-plate support, and means for supplying fluid-pressure to the main exterior cylinder to thereby simultaneously raise the stripping-plate support, the pattern-plate support, and the stool-plate support, and means for supplying fluid-pressure to the secondary cylinder to operate the stool-plate support independent of the stripping-plate and pattern-plate supports. 40
7. In a molding-machine, a cross-head, a main exterior cylinder carrying the stripping-plate and pattern-plate supports, a secondary cylinder arranged within the main exterior cylinder, a stool-plate support carried thereby, arms projecting upwardly from the stool-plate support, the ends of said arms being disposed substantially in the plane of the stripping-plate support, means for supplying fluid-pressure to the main cylinder for simultaneously raising and lowering the stripping-plate support, the pattern-plate support, and the stool-plate support to effect the ramming operation, and means for thereafter supplying fluid-pressure to the secondary cylinder to raise the stool-plate support and its upwardly-projecting arms to raise the mold from the patterns. 55
8. In a molding-machine, the combination of a movable cross-head, a stripping-plate support, a pattern-plate support, and a stool-plate support, means for simultaneously raising and lowering all of said supports to effect the ramming operation, a second means for raising and lowering the stool-plate support in separating the mold from the pattern, and devices controlled by the position of the cross-head for rendering the first-mentioned means inoperative when the cross-head is not in position for the ramming operation, and the second means inoperative when the cross-head is in said position. 70
9. In a molding-machine, the combination of a stripping-plate support, a pattern-plate support, and a stool-plate support, a cross-head, pivotally-mounted side bars supporting said cross-head either in position above said supports or to one side thereof, means for simultaneously moving all of said supports to and from the cross-head during the ramming operation, a second means for raising and lowering the stool-plate support independently, and devices for rendering the first of the above-mentioned means inoperative when the cross-head is in position to one side of said supports, and the second means inoperative when the cross-head is in position above said supports. 85
10. In a molding-machine, a main cylinder carrying the stripping-plate and pattern-plate supports, a secondary cylinder carrying the stool-plate supports, a cross-head pivotally mounted to swing to position either above or to one side of said supports, means for supplying fluid-pressure to the main cylinder for simultaneously raising and lowering all of said supports, a second means for supplying fluid-pressure to the secondary cylinder to independently raise and lower the stool-plate support, and devices controlled by the position of the cross-head for rendering the first of the above-mentioned means inoperative when the cross-head is in position to one side of said supports, and for rendering the second means inoperative when the cross-head is in position above said supports. 90
11. In a molding-machine, the combination of a main cylinder carrying stripping-plate and pattern-plate supports, a secondary cylinder carrying a stool-plate support and having upwardly-projecting arms the ends of which are normally in substantially the plane of the stripping-plate support, a cross-head, pivotally-mounted side arms carrying said cross-head, separate conduits leading from a source of fluid-supply to each of said cylinders, valves disposed in said conduits and having portions projecting into the path of movement of one of the side arms of the cross-head to 100
- 120
- 125
- 130

thereby close the valve in the conduit leading to the main cylinder when the cross-head is in position to one side of said supports, and to close the valve in the conduit leading to the 5 secondary cylinder when the cross-head is in position above said supports.

12. In a molding-machine, the combination of a main cylinder carrying stripping-plate and pattern-plate supports, a secondary cylinder disposed within the main cylinder carrying a stool-plate support and having upwardly-projecting arms the ends of which are normally in substantially the plane of the stripping-plate support, a cross-head, pivotally-mounted side arms carrying said cross-head, separate conduits leading from a source of fluid-supply to each of said cylinders, valves disposed in said conduits and having portions projecting into the path of movement of one 20 of the side arms of the cross-head to thereby close the valve in the conduit leading to the main cylinder when the cross-head is in position to one side of the said supports, and to close the valve in the conduit leading to the 25 secondary cylinder when the cross-head is in position above said supports.

13. In a molding-machine, the combination of a main cylinder carrying stripping-plate and pattern-plate supports, a secondary cylinder carrying a stool-plate support, a cross-head, side arms pivotally mounted and carrying said cross-head, a bracket carried by said side arms, separate conduits leading from a source of fluid-supply to said main and secondary cylinders, said conduits leading from 30 a point in proximity with the pivotal mounting of the side arms to and from the bracket, and valves and cocks disposed in each of said conduits adjacent the bracket.

40 14. In a molding-machine, the combination

of a main cylinder carrying stripping-plate and pattern-plate supports, a secondary cylinder carrying a stool-plate support, a cross-head, side arms pivotally mounted and carrying said cross-head, a bracket carried by said side arms, 45 separate conduits leading from a source of fluid-supply to said main and secondary cylinders, said conduits leading from a point in proximity with the pivotal mounting of the side arms to and from the bracket, and valves 50 or cocks disposed in each of said conduits adjacent the bracket, auxiliary valves also disposed with relation to each of said conduits, and means for automatically closing one and opening the other of said auxiliary valves as 55 the side arms are moved on their pivotal mounting.

15. In a molding-machine, the combination of a supporting-frame, side arms pivotally mounted thereon and carrying a cross-head, 60 a pivotally-mounted cylinder also carried by said frame, a piston connected to a side arm, means for introducing fluid-pressure into said cylinder for moving the cross-head from its vertical position to one side thereof, a second 65 cylinder also pivotally mounted on said frame and a spring connection between said second cylinder and the lower end of a side arm to return the cross-head to its vertical position, the pivotal mounting of the said cylinders 70 permitting them to follow the change in angular relation of the side arms.

In testimony whereof I have hereunto affixed my signature this 8th day of July, A. D. 1903.

FREDERICK W. HALL.
